UNITED STATES PATENT OFFICE.

JAMES D. BOBBITT, OF MADISONVILLE, KENTUCKY.

SILO.

1,214,418.

Specification of Letters Patent. Patented Jan. 30, 1917.

Application filed March 27, 1915. Serial No. 17,439.

To all whom it may concern:

Be it known that I, JAMES D. BOBBITT, a citizen of the United States, residing at Madisonville, in the county of Hopkins and 5 State of Kentucky, have invented certain new and useful Improvements in Silos, of which the following is a specification.

The invention relates to certain improvements in the construction of silos, and the 10 like; and the objects and nature of the invention will be readily understood by those skilled in the art in the light of the following explanation of the accompanying drawings illustrating what I now believe to be 15 the preferred embodiment or mechanical expression of my invention from among other forms and arrangements within the spirit and scope thereof.

It is characteristic of the silo of my invention that the cross bars traversing the vertical opening of the silo and forming parts of the silo ladder, are screwed into the couplings uniting the sections of upright pipe lengths embedded in the vertical monolithic 25 columns that fill the hollow tile blocks forming the silo door posts, and that these cross bars extend through notches in certain blocks and are thereby removed from the mortar or cement joints between the super- 30 imposed blocks, and that these cross bars are not supported by the blocks or in said joints, and that said bars are directly upheld by said pipe lengths and the couplings so that the heavy load thrown on said bars by 35 the workmen passing up and down the ladder, is directly sustained by said pipe lengths, thereby avoiding loosening of and damage to said joints and the blocks.

It is an object of the invention to provide 40 a silo embodying the hereinbefore mentioned characteristics.

The invention consists in certain novel features of construction and in combinations and arrangements as more fully and 45 particularly set forth and specified herein- after.

Referring to the accompanying drawings: Figure 1, is a perspective view illustrating a portion of a silo constructed in accordance with my invention. Figs. 2, 3, 4, 50 5, and 6, are detail views.

In the particular example illustrated, I

show a silo or circular or other building wall erected on a concrete bed or base 1.

The wall is composed of similar super- 55 imposed horizontal courses of blocks, the blocks of each course breaking joints with the blocks of the adjacent courses. This wall is built to form a vertical opening preferably extending from the base to the top of 60 the wall. Each course is composed of a series of hollow blocks 2, and two end blocks 3, 3^a, one of which is a half block, and the end blocks are arranged in vertical 65 series to form the casing or opposite vertical 70 jambs of said vertical opening. The blocks are preferably hollow vitrified clay tiles, and are usually so-called radius blocks.

The blocks 2, are arranged horizontally and are longitudinally hollow and formed 75 with vertical and horizontal internal webs or partitions 2^a, and with parallel side walls and flat parallel top and bottom walls. The top wall 2^b, is preferably formed with a top 80 groove or depression 2^c, throughout the length of the block and arranged approximately midway between its side walls and directly over and in the vertical plane of its vertical web or partition, whereby the block is not weakened by the formation of the 85 groove. These blocks are laid with their ends abutting, and the ends of each course are finished by the blocks 3, 3^a.

The end blocks are vertically hollow and 90 the front outer corners 3^b, thereof are pref- 85 erably rounded or beveled off. The end blocks are preferably of the same radial and vertical dimensions as the blocks 2, and have closed rear end walls 3^c.

The top edges of the walls of the end 95 blocks are formed with notches 3^d, to align with the grooves 2^c. The end blocks 3^a, have internal vertical partitions 3^e, while the half blocks 3, are formed by cutting off the rear 100 end portions of blocks 3^a, so that the intermediate cross partitions thereof will form the end walls 3^c, of the half blocks.

Each door jamb is composed of a vertical row of alined end blocks, the blocks 3, alternating with the blocks 3^a, so that the vertical chambers of said blocks register, the vertical chambers of the rear ends of the blocks 3^a, being closed by the blocks 2, of the adjacent courses that overlap the same.

The registering hollow interiors of the end blocks are filled with a body 5, of concrete, cement or the like, preferably so that a monolithic body 5, extends throughout the 5 vertical length of each jamb.

Strong metal rods, posts or uprights 6, are embedded or inclosed within the bodies 5, and extend throughout the lengths of said jambs, preferably one continuous upright 6,

10 to each jamb. Each upright 6, is composed of pipe sections united by T couplings or unions 7, into the vertical ends or legs of which the pipe sections are secured. These unions are arranged at the joints between 15 blocks or courses, and the unions of one upright are arranged opposite those of the other upright and are joined by horizontal pipe lengths 9, at their ends screwed into the horizontal ends or legs of the unions, so 20 that the cross lengths 9, bridge the vertical doorway or opening of the silo. The unions are arranged within the end blocks and the cross pipes 9, extend thereto through the notches in the top edges of the outer end 25 walls of the end blocks.

Reinforcing wires or rods 10, are arranged throughout the lengths of the courses and at their ends are secured to the uprights in the door jambs, preferably by twisting their 30 ends around said uprights. These wires 10, are arranged in the top grooves of the blocks 2, and in the notches in the top edges of the end blocks and brace each course against 35 expanding pressure and tie the jambs to the remainder of the wall, while the uprights tie the end blocks together and the cross pipes tie the jambs together and space the same.

The lower ends of the uprights 6, are 40 preferably buried a substantial distance in the concrete base and are thereby anchored.

The cross pipes 9, are preferably spaced a uniform distance apart so that said pipes will, occur, say every three courses, although 45 the invention is not so limited. For instance, the vertical width of each course of blocks might be approximately ten inches, while the cross pipes would be arranged say thirty inches apart. These cross pipes as 50 well as the uprights are composed of strong comparatively rigid pipe lengths and not only form braces and ties, but also constitute certain of the rungs of a ladder that extends along the vertical opening of the silo. I 55 prefer to space these cross pipes too far apart to form all of the rungs of such a ladder, and provide the intervening rungs by providing the removable door sections 13, with strong rigid horizontally disposed loop-like or outwardly bulged handles 12, at the outer sides thereof. These door sections are arranged one on the other with their vertical edge portions overlapping the inner sides of 60 the door jambs, to close the vertical opening

of the silo and maintain the ensilage within 65 the silo, as will be readily understood by those skilled in the art. These door sections preferably are provided with pivoted clamps or latches 15, arranged at their outer sides to engage and wedge against the jambs to 70 lock the sections in closed position. Those skilled in the art understand how these door sections are applied as the silo is filled and how they are removed as the silo is emptied.

In constructing the silo, the lower end sections of the uprights 6, are firmly anchored in the concrete base and project upwardly therefrom to the height of say about three block courses. These block courses are then laid, the end blocks being slipped into place 80 over the ends of said upright sections. After each course is laid, the reinforcing wire is placed in the top groove thereof and secured at its ends to the upright sections. When the three courses have been laid, the 85 hollow end blocks can be filled with concrete or cement mortar. T's or unions are then screwed onto the upper ends of fixed upright sections, and the cross pipe is screwed thereinto to form the first cross 90 brace 9, and the next upright sections are also screwed into the upper ends of the T's. The next three courses of blocks are then laid, and so on until the silo wall is completed.

What I claim is:

1. A silo having a vertical door opening and comprising door posts for said opening each composed of superimposed hollow tile blocks and intervening joints between said blocks and a vertical monolithic column filling the blocks, metal uprights in said columns and extending approximately throughout the lengths of said posts and each composed of sections having screw threaded ends and screw threaded couplings uniting said sections, and rigid cross bars traversing said opening and forming parts of a ladder and having screw threaded ends by which said ends are secured to said couplings, certain of said blocks being notched for the passage of said rods into the door posts and to remove the rods from said joints, said rods and the load carried thereby being directly sustained by said uprights 115 through the medium of said couplings, substantially as described.

2. A silo having a vertical door opening, and comprising horizontal superimposed courses of blocks, the end blocks of the 120 courses being hollow and forming vertical door posts provided with a concrete filling, metal uprights extending throughout the lengths of said posts and composed of screw threaded pipe sections of uniform length 125 and threaded T couplings uniting said sections, the couplings of one upright being arranged opposite the couplings of the other

upright, the blocks containing said couplings having notches in their horizontal edges alined with the horizontal branches of said couplings, and rigid ladder-rung-forming 5 cross bars traversing said opening and extending through said notches and having threaded ends screwed into said horizontal branches of the couplings, whereby the load carried by said cross bars is directly sus-

tained by said couplings and the uprights, 10 substantially as described.

In testimony whereof I affix my signature in presence of two witnesses.

JAMES D. BOBBITT.
